ADHESIVE TAPE DISPENSER

Nicholas Williams, Scarsdale, and Tadeusz R. Wolyniec,
Pelham, N. Y.

Application November 5, 1954, Serial No. 32,972

Term of patent 3½ years

(Cl. D74—1)

Fig. 1.

Fig. 2.

Fig. 3.

Figure 1 is a side elevational view of an adhesive tape dispenser showing our new design;

Figure 2 is a top plan view; and

Figure 3 is a bottom plan view thereof.

The opposite side of the dispenser as shown in Figure 1 presents substantially the same appearance as the side shown.

The roll of tape shown in broken lines on the drawing is for illustrative purposes only.

We claim:

The ornamental design for an adhesive tape dispenser, substantially as shown and described.
